UNITED STATES PATENT OFFICE.

DAVID A. ALEXANDER, OF ROCHESTER, NEW YORK.

BALANCED VALVE.

1,273,804.

Specification of Letters Patent. Patented July 30, 1918.

Application filed May 23, 1917. Serial No. 170,538.

To all whom it may concern:

Be it known that I, DAVID A. ALEXANDER, a citizen of the United States of America, residing at Rochester, in the county of Monroe and State of New York, have invented a new and Improved Balanced Valve, of which the following is a specification.

My invention, while relating to automatically operable valves in general, has more especial reference to dry pipe valves for automatic sprinkler systems.

Heretofore, dry pipe systems have not been recommended for sprinkler work when a wet system could be used for the reason that in order to hold the valve closed the air in the system had to be maintained at a considerably high pressure, and this has been objectionable because too long an interval of time is necessitated for expelling the air and filling the system with water. Furthermore, dry pipe valves have required considerable attention as they have involved mechanical features liable to derangement with the consequent interruption of automatic service, and have been subject to false tripping when the water pressure from the source of supply has been suddenly increased. In the accomplishment of my invention these objectionable features have been overcome by providing the so-called balanced valve which is not only extremely simple in construction but requires but a minimum air pressure to be maintained in the system, and this can remain constant for any and all pressures of the water supply.

The main object, then, of the present invention is to provide a dry pipe valve so constructed and operable as to reduce to a minimum the required air pressure for keeping the valve closed, thereby greatly improving dry pipe systems by making them more quickly responsive in time of fire, for the less air there is to be expelled from the pipes the sooner will water reach the open sprinkler heads.

Another object is to make use of a water column, or static head, as a positive means for opening the valve when the air pressure has been released.

Another object is to provide resilient seats for the valve plates, or closing members, which prevent leakage by compensat-

ing for any possible inaccuracies in construction or adjustment.

Another object is to provide a cushioning means whereby the valve when opening will do so without jarring the parts and with little noise.

A further object is to provide a valve having few movable parts, that is simple, durable and inexpensive in construction, easy of inspection and adjustment, not liable to false tripping and having a straight and unobstructed waterway.

A still further object is to so construct a valve of the character described that it may, if desired, be used as an alarm valve in a wet system.

While I have shown a valve especially adapted for use in dry pipe automatic sprinkler systems, the invention is not limited to valves of this particular character but the principle thereof,—that is, the balance feature,—may be employed in valves for various other purposes. For instance, by a reversal of the valve plates relatively to the partition plate and by a slight modification of the body the valve may be used in a sprinkler system wherein a vacuum is maintained, and such a modification is shown in the drawings.

The invention will first be described and will then be particularly defined in the appended claims.

Reference is made to the accompanying drawings forming a part of this specification, and in which,—

Figure 1 is an enlarged vertical sectional view taken on the line 1—1 of Fig. 4 of a valve constructed in accordance with my invention; Fig. 2, a sectional detail showing a modification of the cushioning means from that seen in Fig. 1; Figs. 3 and 4, side and end elevations, respectively, of the valve; Fig. 5, a sectional detail taken on the line 5—5 of Fig. 6 with the bearing blocks shown in full; Fig. 6, an enlarged sectional view similar to Fig. 1 of the partition plate and portions of the valve body but with the operating parts shown in full; Fig. 7, a sectional view taken on the line 7—7 of Fig. 6; Fig. 8, a plan view from the under side of the right hand valve plate, with respect to Figs. 1 and 6, and showing a portion of the connecting arm and the par-

ition plate; Fig. 9, a sectional view similar to Fig. 7 but showing a modified form of valve plate and seat therefor; and, Fig. 10, a sectional view similar to Fig. 1 of a modification of the valve as will be explained, the valve plates and connecting arm being shown in full lines. In Figs. 1 and 10 the movable parts are shown in dotted lines for the open position of the valves.

10 Similar reference characters refer to similar parts throughout the several views.

Referring first to Figs. 1 to 8, inclusive.

The valve casing or body is formed, preferably, of two substantially similar castings 1 and 2, the part 1 having an inlet 3 for connection to the water supply pipe 4 and the part 2 an outlet 5 for the connection to the main pipe 6 of a sprinkler system. In the side walls of the casing are hand-holes 7 which give access to all interior parts of the valve and are provided with suitable cover plates 8. The body members have outwardly extending flanges 9, through which bolts 10 extend and secure such members to the opposite sides of a partition plate 11. This plate divides the interior of the casing into a water chamber 12 and an air chamber 13 which, when the valve is open, have communication through a cylindrical opening 14 in direct line with the inlet 3 and outlet 5. At 15 is a threaded opening in the valve body to receive a pipe 16 in which is located a test valve to determine the vigor of the water supply. Likewise, 17 is a threaded opening in the valve body just above the priming water level $w-w$ to receive a pipe 18 in which is located a valve for determining that there is no water in the system above such level and, also, for emptying the entire system of sprinklers and piping; while at 19 is a threaded opening in the valve body just below the priming water level to receive a pipe 20 in which is located a valve for determining whether the priming water is up to its required level. The three valves just above mentioned as being located in the pipes 16, 18, and 20 are not shown in the drawings.

Projecting downward from the partition plate 11 are bearing blocks 21 having threaded openings therethrough for receiving studs 22, such studs being held in proper position of lateral adjustment by lock nuts 23 and having their inner ends tapered to engage in correspondingly tapered openings in opposite sides of the upright center portion 24 of the thus pivotally supported connecting arm 25. The body portions of the bearing blocks are preferably square and are held against rotation by engaging in recesses in the partition plate 11, while their upper ends are turned down to engage through openings therefor in the partition plate and threaded to receive the nuts 26 for securely holding them in place. Threaded into the oppo-

site ends of the arm 25 are upwardly extending studs 27 held in proper position of adjustment by lock nuts 28, and these studs are provided with heads 29 curved on their under sides.

Overhanging the opening 14 is a flat metal ring 30 secured by screws, as in Fig. 7, or otherwise to the upper face of the partition plate 11; and secured to the under face of the partition, with its inner diameter less than that of the ring 30, is a similar ring 31. The inner edges of these rings are flanged and together form a resilient seat for the downwardly closing member 32 or valve plate, as it will be hereinafter called.

This valve plate comprises a disk 33 seated on the ring 30 and a clamping plate 34 of slightly less diameter bolted to the under face of the disk and seated on the ring 31. The member 34 has a central opening for receiving the left hand stud 27 and is counter sunk to permit a relative universal movement of the head 29.

In the under face of the partition plate is a circular recess forming a chamber 35 open to the atmosphere, while secured to the partition and overhanging such recess is a flat metal ring 36 having its inner edge flanged and forming a resilient seat for the upwardly closing valve plate 37. This plate comprises a disk 38 to the under side of which is bolted a clamping plate 34 having a central opening for receiving the right hand stud 27 and counter sunk to permit a relative universal movement of the head 29. It will be understood that the valve plates 32 and 37 may be secured to the ends of the connecting arm 25 by any form of universal connection, although I prefer to make use of that such as just above described. The coil springs 39, as shown housed in the valve plates 32 and 37 and in the heads of the studs 27, hold the valve plates from freedom of play on the studs and against their respective seats when the valve is being set.

Any leakage around the valve plate 32 will be carried off through the duct 40 in the partition plate 11 and communicating with the drain pipe 41, while any leakage around the valve plate 37 into the recess 35 will be carried off through the duct 42 in the partition plate and communicating with the drain pipe 43, such drains having connections as will later be described.

The centers of the valve plates 32 and 37 are equidistant and on opposite sides of the axis of rotation of the arm 25 with the plate 32 for closing the opening 14 in the partition 11 being seated against and the plate 37 with the water pressure, and it is preferable that in this modification of the valve the areas of both plates exposed to the water pressure be equal. Thus, the plates will be opposed to each other with a counterbal-

ancing effect; for the water pressure, whether high or low, on the plate 32 to open the valve will be equalized by its pressure on the plate 37 to hold the valve closed.

- 5 With the valve closing members thus balanced there must necessarily be provided some positive means for automatically opening the valve at the proper time, and I accomplish this in either of two ways, namely, 10 the valve plate 37 may be enough heavier than the plate 32 that the arm 25 will swing by gravity when the air pressure in the system has been released, or a water column comprising a static head acting on the plate 15 37 may be used. The open position for the parts 25, 32 and 37 is seen in Fig. 1, in dotted lines, at 44, 45 and 46, respectively. The air pressure, then, necessary to be maintained in the system need only be high 20 enough to overcome either the tendency of the swinging members to open by gravity or the weight of the water column, or both, should they be used, and I have found five pounds or even less amply sufficient for this 25 purpose. Furthermore the air pressure need not, as required with most valves of this character, be increased as the water pressure is increased but can remain constant and at a low pressure for all water conditions, and 30 the valve will not suffer from the injurious effects of water hammer. The air pressure of the system is exerted through the medium of the priming water in the chamber 13 directly on the valve plate 32 to hold the valve 35 closed, and there is a slight differential in the areas of the outer and inner surfaces of such plate acted on by the air and water, respectively, owing to the plate being seated on the upper surface of the partition 11. 40 This difference in areas may be considerable or practically nothing as preferred. It will be understood, however, that the valve is not to be considered as of the differential type but one in which the parts are balanced by 45 the water pressure for the purpose of reducing to a minimum the air pressure of the system, overcoming the injurious effects of water hammer and preventing false tripping.
- 50 When the air pressure in the system has been released through the opening of a sprinkler head, or otherwise, the valve will automatically open, due to the water column resting on the plate 37, and the parts will 55 swing by gravity to open position in which they will remain without the aid of any sort of latch mechanism until the valve is reset. The valve plates 32 and 37 swing clear of and to one side of the waterway, thus leaving the same entirely unobstructed.

With many dry pipe valves there is a terrific noise and jarring of the parts when the valve trips owing to the contacting of metal parts by the force of water suddenly 60 rushing through the valve. This is an ob-

jectionable feature and one which I have overcome in the manner now to be described.

At 47 in the air chamber 13 is a comparatively short dash-pot open at one end and adjustably supported on the threaded outer end of an angularly disposed rod 48 threaded at its other end into a boss 49 formed on the casing member 2; and threaded into the disk 33 of the valve plate 35 is the stem 50 of a piston plate 51 which is thus rigidly held to and above such disk, the diameter of the piston being slightly less than that of the opening in the member 47. When the valve opens and the parts have almost reached the position in which they are seen in dotted lines in Fig. 1, the piston 51 entering the member 47 will be arrested in its movement by the cushioning effect of the imprisoned air and water and the swinging parts thus brought to a gradual stop as the air and water in the member 47 escape around the edges of the piston.

In Fig. 2 there is shown a preferred modification of the cushioning stop device in which the dash-pot 52, supported on a rod 48, as the member 47, is designed to receive the disk 33 which itself acts as the piston.

Threaded into the partition plate 11 is a pipe 41 in communication with the duct 40 and this pipe is connected to a T having connection with piping 53 leading to the sewer and with piping 54 which, when the valve is open, carries water that effects a ringing of an electric alarm. Any leakage of water around the valve plate 32 will be carried through the duct 40, pipe 41 and drain pipe 53 wherein is located a drip valve 55, but when the valve is open the pressure of water in the piping just described will automatically close the drip valve and all water passing through the duct 40 will be forced through the pipe 54 to effect a ringing of the alarm as stated.

A pipe 43 is threaded into the partition 11 in communication with the duct 42. This pipe is connected to an upright pipe 56 containing a water column acting on the member 37 to open the valve when the air pressure in the system has been released and the pipe 56 is broken to show that the column may be of any desired height. Near the open end of the pipe 56 is a valve 57 opened only when filling the pipe which may be done through the funnel 58 or by having communication with a supply tank, not shown. A lateral 59 having a valve 60 therein, which is closed only when filling the pipe 56, is connected to the upright pipe intermediate the valve 57 and the desired height of the water column; and this pipe 59 has connection to a drain in which is located a drip valve 61.

When seating the valve, the swinging members after first being cleaned and adjusted,—the adjustment of the studs 27 be

ing effected by means of a suitable tool engaging through openings therein,—are held in closed position by the hand or a suitable instrument inserted through one of the 5 hand-holes 7 in the lower casing member 1 until the desired air pressure has been pumped into the system. The hand-hole cover plate 8 is then replaced, the usual gate valve in the water supply pipe opened and 10 the pipe 56 filled to form the water column.

The valve plate 32 being seated against and the valve plate 37 with the water pressure, both having equal areas acted on by such pressure and being equidistant from 15 the axis of rotation of the arm 25, they will oppose each other with a counterbalancing effect. The water column acting on the plate 37 will cause the valve to open, however, when the air pressure in the system 20 has been released and a preponderance of weight being in favor of the plate 37 will cause the arm 25 to rotate by gravity thus effecting a positive opening of the valve independent of the water pressure, and these 25 features overcome what is necessary in most dry pipe valves of the valve having to be "blown" open by water when the air has been released.

Refer now to Figs. 1 and 6.

30 At 62 is shown a plug for closing the opening through the partition 11 into the recess 35 formed in the underside thereof, and should it be desired to use the valve as an alarm valve for what is known as the "wet 35 system" this plug would be removed. In this event the water column would not be used and the area of the valve plate 32 exposed to the water pressure in the chamber 12 would be made greater than that of the 40 valve plate 37.

In Fig. 9 there is shown a partition plate 63 having a port opening 64 which is normally closed by a valve plate 65 comprising a disk 66 and clamping plate 67 bolted 45 thereto. This valve plate is adapted to have universal connection with an arm 25 by means of an adjustable stud 27 similar to that bearing like numeral in Fig. 7, and such stud is provided with a head 29 seated 50 in the clamping plate 67 and held against play by a coil spring 39 contained in a housing formed in the bolt head 29 and in the disk 66. The valve seat comprises outer and inner circular flanges 68 and 69, respectively, projecting upward from the partition 63, the outer one of which is formed on a resilient ring 70 secured to the partition and engages the disk 66, while the inner one is formed on the partition and engages a 55 resilient ring 71 secured to the disk. Any leakage into the channel between the flanges 68 and 69 would be carried off through a duct, not shown, but similar to that shown at 40 in Figs. 1 and 6.

60 65 Refer now to Fig. 10.

In this view there is shown a modification of my present invention adapted for use in an automatic sprinkler system having a vacuum in the pipes thereof instead of air or water under pressure.

The valve casing is substantially similar to that shown in Fig. 1 and is formed of two castings 72 and 73, the part 72 having an inlet 74 and the part 73 an outlet 75. In the side walls of the casing are hand holes 7 75 provided with suitable cover plates 8, as in Fig. 1. These body members are bolted to opposite sides of a partition plate 76 which divides the interior of the casing into a water chamber 77 and an upper part which in 80 turn is subdivided by a partition 78 into a vacuum chamber 79 terminating in the outlet 75 and an air chamber 80 having an opening 81 affording communication with the atmosphere. The valve body members are 85 provided with openings 82 and 83 similar to and for the same purpose as the openings 15 and 17, respectively, in Fig. 1.

The partition plate 76 has an opening 84 affording communication between the water 90 chamber and the vacuum chamber and aligned with the inlet and outlet of the valve in order to form a straight waterway, and, also, an opening 85 affording communication between the water chamber and the air 95 chamber.

The valve plates 86 and 87 for closing the openings 84 and 85, respectively, are similar to the valve plates 37 and 32, respectively, of Figs. 1 and 6, and have similar universal connection by studs 27 to the opposite ends of an arm 88 fulcrumed between the two valve plates on the under side of the partition in the same manner as the arm 25. It will be noticed that the valve 105 plate 86 for closing the opening 84 between the water chamber and vacuum chamber is seated on the reverse side of the partition from that of the valve plate 32 in Fig. 1 and, also, that the arm 88 will swing in the 110 opposite direction from that of the arm 25. The open positions for the valve plates 86, 87 and arm 88 are indicated in dotted lines at 89, 90 and 91, respectively. A resilient seat is provided for the valve plate 86 similar to that for the plate 32 of Fig. 1 except that it is presented downward instead of upward and, likewise, a resilient seat is provided for the valve plate 87 similar to that for the plate 37 of Fig. 1 except that it is 120 presented upward instead of downward.

The centers of the valve plates 86 and 87 are equidistant from the axis of rotation of the arm 88 and the areas of the two plates exposed to the water pressure are preferably 125 equal, although a slight preference may be made in favor of the plate 87. There is a preponderance of weight in favor of the valve plate 86 to cause the arm to swing by gravity when air has been admitted to the 130

vacuum chamber 79 through the opening of a sprinkler head or otherwise.

The operation of this valve is the same as that of the one shown in and described with reference to Figs. 1 and 6, with the exception that the parts swing in the reverse direction and instead of an air pressure being used in the system to hold the valve closed a vacuum is used to perform this same function. Any leakage around the valve plate 86 would be carried off through the communicating duct 40 and drain pipes 41 and 53 similar to those shown in and referred to with regard to Fig. 1, and when the valve is open water through the duct 40 will pass through the pipe 54 and cause a ringing of the alarm.

What I claim is:

1. A valve of the character described comprising a casing having two chambers into one of which is the inlet and from the other the outlet of the valve; a partition having a port opening affording communication between the two chambers and an opening to the exterior of the casing; valve plates seated on opposite sides of said partition, one of said plates closing the said port opening and the other the said opening to the exterior of the casing and both being exposed to the water pressure; and a pivotally supported arm connecting said valve plates, whereby they oppose each other with a counterbalancing effect.

2. A valve of the character described comprising a casing having a straight waterway and two chambers into one of which is the inlet and from the other the outlet of the valve; a partition having a port opening alined with the waterway affording communication between the two chambers and an opening to the exterior of the casing; valve plates seated on opposite sides of said partition, one of said plates closing the said port opening and the other the said opening to the exterior of the casing and both being exposed to the water pressure; and a pivotally supported arm connecting said valve plates, whereby they are opposed to each other with a counterbalancing effect, and adapted upon rotation to carry the said port closing plate to one side of the waterway.

3. A valve of the character described comprising a casing having a straight waterway and two chambers into one of which is the inlet and from the other the outlet of the valve; a partition having a port opening alined with the waterway affording communication between the two chambers and an opening to the exterior of the casing; valve plates seated on opposite sides of said partition, one of said plates closing the said port opening and the other the said opening to the exterior of the casing and both being exposed to the water pressure; bearing members carried by said partition; studs ad-

justable in said bearing members; and a connecting arm for said valve plates pivotally supported on said studs, whereby the plates are opposed to each other with a counterbalancing effect, and adapted upon rotation 70 to carry the said port closing plate to one side of the waterway.

4. A valve of the character described comprising a casing having a straight waterway and two chambers into one of which is the 75 inlet and from the other the outlet of the valve; a partition having a port opening alined with the waterway affording communication between the two chambers and an opening to the exterior of the casing; a 80 downwardly closing valve plate for said port opening seated with the air pressure and against the water pressure; an upwardly closing valve plate for said opening to the exterior of the casing seated with the water 85 pressure; and a pivotally supported arm connecting said plates, whereby they are opposed to each other with a counterbalancing effect, and adapted upon rotation to extend through the said port opening and carry the 90 first named plate to one side of the waterway.

5. A valve of the character described comprising a casing having a straight waterway and two chambers into one of which is the 95 inlet and from the other the outlet of the valve; a partition having a port opening alined with the waterway affording communication between the two chambers and an opening to the exterior of the casing; a 100 downwardly closing valve plate for said port opening seated with the air pressure and against the water pressure, an upwardly closing valve plate for said opening to the exterior of the casing seated with the water 105 pressure, the areas of said valve plates exposed to the water pressure being equal; and an arm connecting said plates pivotally supported midway between their center, whereby they are opposed to each other with a 110 counterbalancing effect, and adapted upon rotation to extend through the said port opening and carry the first named plate to one side of the waterway.

6. A valve of the character described comprising a casing having a straight waterway and two chambers into one of which is the inlet and from the other the outlet of the valve; a partition having a port opening alined with the waterway affording communication between the two chambers and an opening to the exterior of the casing; a downwardly closing valve plate for said port opening seated with the air pressure and against the water pressure; an upwardly 120 closing valve plate for said opening to the exterior of the casing seated with the water pressure, the areas of said valve plates exposed to the water pressure being equal; and an arm connecting said plates pivotally sup- 125

ported midway between their centers, whereby they are opposed to each other with a counterbalancing effect, and adapted upon rotation to extend through the said port 5 opening and carry the first named plate to one side of the waterway, a preponderance of weight being in favor of the second named plate causing the arm to rotate by gravity when the air pressure is released.

10 7. A valve of the character described comprising a casing having an inlet and an outlet; a partition having a port opening; valve plates seated on opposite sides of said partition, one of such plates closing the said 15 opening and both being exposed to the water pressure; means for containing a column of water comprising a static head acting on the other of said plates to open the valve; and a pivotally supported arm connecting said 20 valve plates, whereby they are opposed to each other with a counterbalancing effect.

8. A valve of the character described comprising a casing having a straight waterway; a partition having a port opening alined 25 with the waterway; valve plates seated on opposite sides of said partition, one of such plates closing the said opening and both being exposed to the water pressure; a pivotally supported arm connecting said valve 30 plates, whereby they are opposed to each other with a counterbalancing effect, and adapted upon rotation to carry the said port closing plate to one side of the waterway; and means for containing a column of water 35 comprising a static head acting on the other of said plates to open the valve.

9. A valve of the character described comprising a casing having a straight waterway; a partition having a port opening 40 alined with the waterway; valve plates seated on opposite sides of said partition, one of such plates closing the said opening and both being exposed to the water pressure; a pivotally supported arm connecting 45 said valve plates, whereby they are opposed to each other with a counterbalancing effect, and adapted upon rotation to carry the said port closing plate to one side of the waterway; and means for containing a column of water 50 comprising a static head acting on the other of said plates to open the valve, a preponderance of weight being in favor of such last named plate causing the arm to rotate by gravity when the valve is opened.

55 10. A valve of the character described comprising a casing having an air chamber and a water chamber; a partition having a port opening affording communication between the two chambers and an opening to 60 the exterior of the casing; valve plates seated on opposite sides of said partition, one of said plates closing the said port opening and the other the said opening to the exterior of the casing and both being exposed to the 65 water pressure; a pivotally supported arm

connecting said valve plates and adapted upon rotation when the air pressure has been released to swing them to open position; a piston carried by said arm; and a member forming a compression chamber within the 70 said air chamber adapted to receive said piston for the purpose specified.

11. A valve of the character described comprising a casing having an air chamber and a water chamber; a partition having a port opening affording communication between the two chambers and an opening to the exterior of the casing; valve plates seated on opposite sides of said partition, one of said plates closing the said port opening and the other the said opening to the exterior of the casing and both being exposed to the water pressure; a pivotally supported arm connecting said valve plates and adapted upon rotation when the air pressure has 80 been released to swing them to open position; a piston carried by said arm; and an adjustably supported member forming a compression chamber within the said air chamber adapted to receive said piston for 85 the purpose specified.

12. A valve of the character described comprising a casing having two chambers into one of which is the inlet and from the other the outlet of the valve; a partition 95 having an opening affording communication between the two chambers and a recessed chamber formed therein having communication with the exterior of the casing; a valve plate for closing said opening seated on one side of the partition with the air pressure and against the water pressure; a valve plate for covering said recessed chamber seated on the opposite side of the partition with the water pressure; and an arm connecting said 100 plates and fulcrumed between the two, whereby they are opposed to each other with a counterbalancing effect, said arm adapted to rotate when the air pressure is released, thus unseating said plates and opening the 110 valve.

13. A valve of the character described comprising a casing having a straight waterway and two chambers into one of which is the inlet and from the other the outlet of the 115 valve; a partition having an opening affording communication between the two chambers and a recessed chamber formed therein having communication with the exterior of the casing; a valve plate for closing said opening seated on one side of the partition with the air pressure and against the water pressure; a valve plate for covering said recessed chamber seated on the opposite side of the partition with the water pressure; and an arm connecting said plates and fulcrumed between the two, whereby they 125 are opposed to each other with a counterbalancing effect, said arm adapted to rotate when the air pressure is released to unseat 130

said plates and carry them to one side of the waterway.

14. A valve of the character described comprising a casing having a straight waterway and formed of two castings; a partition removably held between such castings which divides the casing into two chambers into one of which is the inlet and from the other the outlet of the valve, such partition having an opening affording communication between the two chambers and a recessed chamber formed therein having communication with the exterior of the casing; a valve plate for closing said opening seated on one side of the partition with the air pressure and against the water pressure; a valve plate for covering said recessed chamber seated on the opposite side of the partition with the water pressure; and an arm connecting said plates and fulcrumed between the two, whereby they are opposed to each other with a counterbalancing effect, said arm adapted to rotate when the air pressure is released to unseat said plates and carry them to one side of the waterway.

15. A valve of the character described comprising a casing having a straight waterway and two chambers into one of which is the inlet and from the other the outlet of the valve; a partition having an opening affording communication between the two chambers; a recessed chamber formed therein having communication with the exterior of the casing; and an opening communicating with said recessed and said outlet chambers; a valve plate for closing said first named opening seated on one side of the partition with the air pressure and against the water pressure; a valve plate for covering said recessed chamber seated on the opposite side of the partition with the water pressure; an arm connecting said plates and fulcrumed between the two, whereby they are opposed to each other with a counterbalancing effect, said arm adapted to rotate when the air pressure is released

to unseat said plates and carry them to one side of the waterway; and a removable member for normally closing the said opening between the recessed and the outlet chambers.

16. In a valve, a partition plate having an opening therethrough and a recessed chamber formed therein; valve plates seated on opposite sides of the partition, one of such plates closing said opening and the other covering said chamber; an arm fulcrumed between the plates and connected thereto; and resilient seats for said valve plates comprising flat rings secured to the partition and extending over the edges of said opening and said chamber.

17. In a valve, a partition having an opening therethrough and a recessed chamber formed therein; valve plates resiliently seated on opposite sides of the partition, one of such plates closing said opening and the other covering said chamber; and an arm fulcrumed between the plates and connected thereto.

18. In a valve, a partition having an opening therethrough and a recessed chamber formed therein; valve plates resiliently seated on opposite sides of the partition, one of such plates closing said opening and the other covering said chamber; and an arm fulcrumed between the plates and having universal connection therewith, for the purpose specified.

19. A valve comprising a casing having a water chamber and an air chamber; a partition having a port opening affording communication between the two chambers and an opening to the exterior of the casing; valve plates resiliently seated on opposite sides of the partition, one of such plates closing said port opening and the other the said opening to the exterior of the casing; and an arm fulcrumed between the said plates and connected thereto.

DAVID A. ALEXANDER.
